(57) CLAIM

I claim the design for a portable golf ball cleaner, as shown and described.

DESCRIPTION

FIG. 1 is a Top left perspective view of the ornamental design of the instant invention;

FIG. 2 is a top plan view thereof, the lid removed for clarity of illustration; and,

FIG. 3 is a right side elevational view of FIG. 1, the lid shown in a closed position.

1 Claim, 1 Drawing Sheet

FIG. 1

FIG. 2
